PURMORT BRADFORD, OF NEW HAVEN, CONNECTICUT, ASSIGNOR TO
SARGENT AND COMPANY OF THE SAME PLACE.

Letters Patent No. 71,965, dated December 10, 1867.

IMPROVED DOOR-LATCH.

The Schedule referred to in these Letters Patent and making part of the same.

TO ALL WHOM IT MAY CONCERN:

Be it known that I, PURMORT BRADFORD, of New Haven, in the county of New Haven, and State of Connecticut, have invented a new Improvement in Door-Latches; and I do hereby declare the following, when taken in connection with the accompanying drawings, and the letters of reference marked thereon, to be a full, clear, and exact description of the same, and which said drawings constitute part of this specification, and represent, in—

Figure 1, a front view,

Figure 2 an edge view; and in

Figures 3 and 4 rear or internal views, to illustrate the manner of adjustment for right or left-hand doors.

This invention relates to an improvement in the construction of latches, such as are used for small or cupboard doors, its object being to make the latch adjustable either for a left or right-hand door, and consists in the construction of the latch with a hole or notch upon its opposite sides, so that a pivot centrally located in the case, and passed through either one of the two holes or notches in the latch, will fix the latch either for a right or left-hand door, as the case may be.

To enable others to construct my improvement, I will proceed to describe the same, as illustrated in the accompanying drawings.

A is the case or plate, to which the latch is attached. B, the latch, is formed as seen in figs. 3 and 4, with a notch or hole, a, upon one side, and b upon the other, and nearly in line with the corresponding edge of the latch itself, and so that a pivot or screw inserted through a central hole, f, in the plate, will pass through or into one of the notches or holes in the latch-bolt, as seen in figs. 3 and 4. As in fig. 3, through the notch or hole a for a left-hand door, and reversed as in fig. 4, so as to pass through the hole or notch b upon the opposite side, for a right-hand door. I prefer to insert the latch-bolt within the case, as shown in the drawings, yet it may be upon the outside of the plate, if desired. If upon the outside, the bearing of the latch upon the pivot should be by a hole through the latch; but upon the inside, a notch, as shown in the drawings, is all that is required, the lower side of the latch being held against the pivot by the rim of the case. For convenience of operation, I fix a knob, C, to the latch-bolt, and if within a case, a slot through the case must be formed, to permit the raising of the latch, as denoted in red, fig. 1. The keeper or catch for this latch may be of any of the known reversible constructions.

The plate is secured to the door, one of the screws passing through and forming the pivot f. This is the better plan of attachment; yet, if preferred, the pivot may be fixed to or formed upon the plate, and other means used for securing the plate to the door.

I do not broadly claim a latch adjustable so as to be adapted to a right or left-hand door; but

What I do claim as new and useful, and desire to secure by Letters Patent, is—

The construction of the latch-bolt, with the pivot-bearings a and b upon opposite sides, combined with a single central pivot upon the plate, so as to be adjustable for a right or left-hand door, and the said plate constructed with a slot through which the latch is operated, in the manner herein set forth.

PURMORT BRADFORD.
